UNITED STATES PATENT OFFICE.

MAX F. OESER, OF BIRMINGHAM, ALABAMA.

HEATER CONTROL FOR PAPER-RULING MACHINES.

Application filed October 25, 1924. Serial No. 745,848.

My invention relates to paper ruling machines and particularly to means for automatically controlling the drier means so that the blanket shall not be injured thereby when 5 the machine is stopped for any purpose.

Heretofore, in the operation of paper ruling machine, whenever the machine is stopped and the blanket brought to rest, it is necessary for the operator to cut off the 10 drying heater as otherwise the blanket remaining stationary above the heater would be damaged or burned. The operators are often careless in cutting off the heaters and the result is that the blankets, which are very 15 expensive, are frequently damaged.

I have conceived that automatic means may be provided which will either cut out the drying heater or reduce its temperature, whenever the blanket is stopped so that the 20 blanket, though stationary above it, would not be injured thereby.

More particularly, the object of my invention is to connect a control mechanism for the heater with the start and stop mechanism of the ruling machine in such manner 25 that the stopping of the machine will cut off the heater.

My invention further comprises the novel details of construction and arrangements of 30 parts, which in their preferred embodiment only are illustrated in the accompanying drawings which form a part of the specification, and in which:—

Fig. 1 is a side elevation of a ruling machine, the ruling devices proper being omitted.

Fig. 2 is a perspective detail view showing a typical gas burning heater for drying the 35 blanket connected to a conventional clutch 40 throw for the blanket drive.

Fig. 3 is an enlarged detail view of a gas burner and valve mechanism; and

Fig. 4 is a plan view of the clutch rod and the parts directly connected thereto.

Similar reference numerals refer to similar parts throughout the drawings.

I have illustrated my invention as applied to a paper ruling machine which may be of any suitable type, that shown being a conventional ruling machine which comprises a main frame work having uprights 1 and 2 which support horizontal frame members 3 and 4. On the uprights 2 is a feed table 5 and the upper ends of these uprights project 55 well above the frame and carry underhung arms 6 in which a roller 7 is journaled. The

frame members 4 support standards 8 having a roller 9 journaled at their top and a roller 10 journaled at their bottom. Strings pass around these several rollers, 9 and 10 and over the segment board 12 to a roller 13 near the feed table 5. This arrangement is of conventional design and forms no particular part of my invention. The roller 13 is driven by a gear 14 meshing a gear 15 suitably 60 mounted in the frame and driven by a sliding clutch gear 16 having fast and loose members which are driven from any suitable source of power and by any available transmission, this being conventionally illustrated 65 by a pulley driven gear 17. The sliding clutch gear 16 is controlled by a clutch arm 18 having a clutch engaging yoke at its lower end and having its upper end connected to a collar 19 fast on the clutch throw rod 20. 70 The clutch arm 18 is mounted to rock on a bracket 21 fast on an upright 2. I provide a second bracket 22 on said upright and pivot thereon intermediate its ends a lever 23 disposed for horizontal movement and having 75 one end connected by a link 24 with a clamp sleeve 25 applied rigidly to the clutch rod 20. The other end of the lever 23 carries a pin 26 working in an elongated slot 27 in a T-shaped rocker arm 28, the ends of the T- 80 head of said arm being connected by chains, wires or other suitable connectors 29 and 30 with a rocker 31 made fast at its center to the stem 32 of the gas supply valve 33 in the valve body 34. This valve 33 is an ordinary 85 one-way valve for controlling the delivery of gas through the Bunson tube 35 to a burner 36, there being a pilot burner 37 connected by a tube 38 with the gas supply ahead of the valve 33.

The manner in which the rocker elements 31 and 28 are connected causes them to be rotated together and the arrangement of parts is such that when the clutch rod 20 is shifted to throw out the clutch, the valve will be turned 90 to shut off the supply of gas to the burner 36. The burner 36 delivers its products of combustion through a cone 39 to a perforated tube having any desired number of intermediate coils 40 which pass back and 95 forth transversely of the machine and finally discharge into an upright pipe 41 leading to the atmosphere. The coils 40 are arranged between the upper and lower middle flights of the blanket 42. The blanket shown 100 is of the endless type, but obviously any standard type of blanket may be employed.

As shown, this blanket passes between the roller 43, driven by the gear 15, and the roller 13 driven by the gear 14 and hence passes about a roller 44 at the left hand end of the 5 machine and then downwardly and about the roller 45 at the right hand end of the machine, and then rearwardly under the heater coils 40 around a roller 46 on a vertical frame member 47, and hence about a 10 roller 48 in the standards 2 and upwardly about a roller 49 and back to the roller 43. Rollers 50 and 51, mounted in uprights 47 and 52, support the flight of the blanket about the heater coils 40.

15 In operation, assuming the clutch thrown to couple the drive for the blanket, the latter will be continuously driven as will also the strings 11 and the gas burner will be turned on full flame. Whenever, for any 20 reason, it is desired to stop the machine, the clutch rod is shifted in the opposite direction and this motion acts simultaneously both to intercept the drive to the blanket feed rolls and to turn off the supply valve 25 to the gas burner, thus cutting off the drier burner and keeping it off until the clutch rod is again thrown to start the blanket drive when the valve is again turned on full and the gas, being ignited by the pilot flame, 30 will again supply the heat to the coils 40. By this arrangement, the heater cannot be left going while the blanket is at rest and thus the blanket is at all times automatically protected against damage from the drier 35 heater.

It is to be understood that the sheets of paper which are fed onto the blanket between the rolls 13 and 43, pass on top of the blankets under the ruling appliances and 40 then are carried along under the blankets by means of endless strings 53 which pass from an upper roller 54 onto the blanket and follow it about the rollers 44 and 45 to the roller 55 and thence pass over the roller 45 56 and around roller 57 and return to the roller 54. They thus hold the sheets face down in passing over and face up in passing under the heating coils 40 and the heat in these coils will serve to dry the ruling on 50 the paper sheets, the latter being discharged at the roll 46 to a lay-boy not shown.

It is to be understood that the heater shown is typical of any available heater and that the operation of the rocker 31 may cut 55 off the heat entirely or lower it to a safety point where it will not damage the blankets. I claim broadly the idea of providing means which will respond automatically to the starting and stopping of the blanket drive 60 to intercept heat from the drier in such

manner or to such extent as will prevent damaging the blanket.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a paper ruling machine having a blanket, a drive therefor and a drying heater having a closed pipe coil for the products of combustion passing between flights of the blanket, means to interrupt the drive to the blanket, and means automatically responsive to the interruption of the blanket drive to cut off the heater.

2. In a paper ruling machine having a blanket, a clutch controlled drive therefor, a drying heater having a closed pipe coil for the products of combustion passing between flights of the blanket, and connected elements to cut off the heater simultaneously with the throwing out of the clutch.

3. A paper ruling machine according to claim 2, in which the connected element will automatically restart the heater when the clutch is thrown in.

4. In a paper ruling machine, a blanket and a drive therefor having a clutch control, a drying heater comprising a gas burner remote from the blanket with a main control valve and a pilot burner, mechanical connections between the gas control valve and the clutch control adapted to close the valve when the clutch is opened and to open the valve when the clutch is closed, and a pipe coil forming part of the flue for the products of combustion from the heater, which coil is interposed transversely of the machine between flights of the blanket.

5. In a paper ruling machine, a clutch controlled drive for the blanket of the machine, a drier burner having a heating coil interposed between flights of the blanket, a valve for said burner, a clutch operating rod, a rocker operably connected to and reversely movable by said clutch rod, and connections to transmit both rocker movements to open or close the valve, and a pilot burner for the heater.

6. A paper ruling machine according to claim 5, in which the rocker is of T-type with its connections to the burner valve formed by flexible wire cables.

In testimony whereof I affix my signature.
MAX F. OESER.
